(57) **ABSTRACT**

A new and distinct cultivar of *Calibrachoa* plant named 'Balcabinsta', characterized by its deep pink-colored flowers having a yellow and cream star-pattern, medium green-colored foliage, and moderately vigorous, mounded to trailing growth habit, is disclosed.

1 Drawing Sheet

1

Latin name of genus and species of plant claimed: *Calibrachoa×hybrida*.

Variety denomination: 'Balcabinsta'.

BACKGROUND OF THE INVENTION

The present invention relates to a new and distinct cultivar of *Calibrachoa* plant botanically known as *Calibrachoa×hybrida* and hereinafter referred to by the cultivar name 'Balcabinsta'.

The new cultivar originated in a controlled breeding program in Guadalupe, Calif. during May 2013. The objective of the breeding program was the development of *Calibrachoa* cultivars with attractive flower coloration, medium green-colored foliage, and a moderately vigorous, mounded to trailing growth habit.

The new *Calibrachoa* cultivar is the result of cross-pollination. The female (seed) parent of the new cultivar is the proprietary *Calibrachoa×hybrida* breeding selection coded 189B-(4).1, U.S. patent application Ser. No. 13/420,359, characterized by its medium red-colored flowers having a yellow star-pattern, medium green-colored foliage, and moderately vigorous, mounded growth habit. The male (pollen) parent of the new cultivar is the proprietary *Calibrachoa×hybrida* breeding selection coded 189B-(4).4, U.S. patent application Ser. No. 13/420,359, characterized by its medium red-colored flowers having a yellow star-pattern, medium green-colored foliage, and moderately vigorous, mounded growth habit. The new cultivar was discovered and selected as a single flowering plant within the progeny of the above stated cross-pollination during November 2013 in a controlled environment in Guadalupe, Calif.

Asexual reproduction of the new cultivar by terminal stem cuttings since November 2013 in Guadalupe, Calif. and

2

West Chicago, Ill. has demonstrated that the new cultivar reproduces true to type with all of the characteristics, as herein described, firmly fixed and retained through successive generations of such asexual propagation.

5

SUMMARY OF THE INVENTION

The following characteristics of the new cultivar have been repeatedly observed and can be used to distinguish 'Balcabinsta' as a new and distinct cultivar of *Calibrachoa* plant:

1. Deep pink-colored flowers having a yellow and cream star-pattern;
2. Medium green-colored foliage; and
3. Moderately vigorous, mounded to trailing growth habit.

Plants of the new cultivar differ from plants of the female and male parents primarily in flower color.

Of the many commercially available *Calibrachoa* cultivars, the most similar in comparison to the new cultivar is SUPERBELLS Cherry Star 'USCAL91001', U.S. Plant Pat. No. 23,232 and U.S. patent application Ser. No. 13/420,359. However, in side by side comparisons, plants of the new cultivar differ from plants of 'USCAL91001' in at least the following characteristics:

1. Plants of the new cultivar have a flower color that is lighter than plants of 'USCAL91001'; and
2. Plants of the new cultivar have slightly smaller flowers than plants of 'USCAL91001'.

25 30 BRIEF DESCRIPTION OF THE PHOTOGRAPHS

The accompanying photographs show, as nearly true as it is reasonably possible to make the same in color illustrations of this type, typical flower and foliage characteristics of the new cultivar. Colors in the photographs differ slightly from

the color values cited in the detailed description, which accurately describes the colors of 'Balcabinsta'. The plants were grown in 4.5-inch pots for 5 weeks in a greenhouse in West Chicago, Ill. Plants were given one pinch at transplant.

FIG. 1 illustrates a side view of the overall growth and flowering habit of 'Balcabinsta'.⁵

FIG. 2 illustrates a close-up view of an individual flower of 'Balcabinsta'.¹⁰

DETAILED BOTANICAL DESCRIPTION

The new cultivar has not been observed under all possible environmental conditions to date. Accordingly, it is possible that the phenotype may vary somewhat with variations in the environment, such as temperature, light intensity, and day length, without, however, any variance in genotype.¹⁵

The chart used in the identification of colors described herein is The R.H.S. Colour Chart of The Royal Horticultural Society, London, England, 2007 edition, except where general color terms of ordinary significance are used. The color values were determined in November 2015 under natural light conditions in West Chicago, Ill.²⁰

The following descriptions and measurements describe plants produced from cuttings from stock plants and grown in a glass-covered greenhouse under conditions comparable to those used in commercial practice. The plants were grown in West Chicago, Ill. in 4.5-inch pots for 5 weeks utilizing a soilless growth medium. Plants were given one pinch at transplant. Greenhouse temperatures were maintained at approximately 70° F. to 77° F. (21° C. to 25° C.) during the day and approximately 65° F. to 68° F. (18° C. to 20° C.) during the night. Greenhouse light levels of 2,500 foot-candles to 6,000 footcandles were maintained during the day. Measurements and numerical values represent averages of typical plants.²⁵

Botanical classification: *Calibrachoa* *hybrida* cultivar Balcabinsta.³⁰

Parentage:

Female parent.—Proprietary *Calibrachoa* *hybrida* breeding selection coded 189B-(4).1, U.S. patent application Ser. No. 13/420,359.⁴⁰

Male parent.—Proprietary *Calibrachoa* *hybrida* breeding selection coded 189B-(4).4, U.S. patent application Ser. No. 13/420,359.⁴⁵

Propagation:

Type cutting.—Terminal stem.

Time to initiate roots.—Approximately 6 to 8 days.

Time to produce a rooted cutting.—Approximately 24 to 28 days.⁵⁰

Root description.—Fibrous.

Rooting habit.—Freely branching.

Plant description:

Commercial crop time.—Approximately 6 to 9 weeks from a rooted cutting to finish in a 10 cm pot.⁵⁵

Growth habit and general appearance.—Moderately vigorous, mounded to trailing.

Size.—Height from soil level to top of plant plane: Approximately 9.5 cm. Width: Approximately 21.0 cm.⁶⁰

Branching habit.—Freely branching, pinching enhances basal branching. Quantity of main branches per plant: Approximately 3.

Branch.—Strength: Moderate. Length: Approximately 10.5 cm. Diameter: Approximately 2.0 mm. Length of central internode: Approximately 1.1 cm. Texture:⁶⁵

Densely glandular pubescent. Gland color: Colorless, transparent. Color of young and mature stems: 144A.

Foliage description:

General description.—Quantity of leaves per main branch: Approximately 14. Fragrance: Slight. Form: Simple. Arrangement on flowering stem: Opposite.

Leaves.—Aspect: At acute angle to stem with tip turning downward. Shape: Elliptic. Margin: Entire. Apex: Broadly acute. Base: Attenuate. Venation pattern: Pinnate. Length of mature leaf: Approximately 2.8 cm. Width of mature leaf: Approximately 1.6 cm. Texture of upper and lower surfaces: Moderately glandular pubescent. Gland color: Colorless, transparent. Color of upper surface of young foliage: 137B with venation of 144D to indistinguishable. Color of lower surface of young and mature foliage: 138A with venation of 138D to indistinguishable. Color of upper surface of mature foliage: 137A with venation of 144D to indistinguishable.¹⁵

Petiole.—Length: Approximately 3.0 mm. Diameter: Approximately 1.0 mm. Texture: Moderately glandular pubescent. Gland color: Colorless, transparent. Color: 144D.²⁰

Flowering description:

Flowering habit.—'Balcabinsta' is freely flowering under outdoor growing conditions with substantially continuous blooming from spring through autumn and year-round in greenhouse environment.²⁵

Lastingness of individual flower on the plant.—Approximately 5 to 7 days.³⁰

Flower description:

General description.—Type: Single, salverform. Quantity per plant: Approximately 7. Fragrance: None detected.³⁵

Bud.—Rate of opening: Generally takes 3 to 4 days for bud to progress from first color to fully open flower. Quantity per plant: Approximately 2.⁴⁰

Bud just before opening.—Shape: Oblong. Length: Approximately 2.0 cm. Diameter: Approximately 5.0 mm. Texture: Densely glandular pubescent. Gland color: Colorless, transparent. Color: Petal portion N74D and tube portion 151D, venation of N77A and 144A.⁴⁵

Corolla.—Diameter: Approximately 3.3 cm.

Petals.—Quantity: 5, fused to form a tube. Shape: Obovate. Margin: Entire. Apex: Obtuse. Length from tube: Approximately 1.2 cm. Length of free portion: Approximately 5.0 mm. Width: Approximately 1.6 cm. Texture of upper surface: Glabrous. Texture of lower surface: Glandular pubescent, dense along venation. Gland color: Colorless, transparent. Color of upper surface when first and fully open: Between N74B and N74C with an overlay of 53A at tube opening; fused margins of NN155D with an overlay of 13A. Color of lower surface when first and fully open: Lighter than N74D with fused margins of NN155B and midveins of 145A.⁵⁰

Corolla tube.—Length: Approximately 2.0 cm. Diameter at distal end: Approximately 7.0 mm. Diameter at proximal end: Approximately 2.0 mm. Texture of inner surface: Glabrous. Texture of outer surface: Densely glandular pubescent. Gland color: Colorless, transparent. Color of inner surface: 13A with

venation of 144A. Color of outer surface: Lighter than 151D with venation of N77A and 144A.

Sepals.—Quantity per flower: 5, fused along lower half. Shape: Lanceolate. Apex: Acute. Length: Approximately 1.3 cm. Width: Approximately 2.0 mm. Texture of upper and lower surfaces: Densely glandular pubescent. Gland color: Colorless, transparent. Color of upper surface: 137A. Color of lower surface: 138B with base of 144B.

Peduncle.—Strength: Strong. Aspect: Acute angle to 10 stem. Length: Approximately 2.5 cm. Diameter: Approximately 1.0 mm. Texture: Densely glandular pubescent. Gland color: Colorless, transparent. Color: 144B.

Reproductive organs.—Androecium: Stamen quantity: 15 5, basifixed. Stamen length: Approximately 1.1 cm. Filament length of fixed portion: Approximately 6.0 mm. Filament color: 145D. Anther shape: Bilobed,

ovoid. Anther length: Approximately 1.0 mm. Anther color: 8B. Pollen amount: Abundant. Pollen color: 8C. Gynoecium: Pistil quantity: 1 per flower. Pistil length: Approximately 1.2 cm. Stigma shape: Funnel. Stigma length: Less than 1.0 mm. Stigma color: 144A. Style length: Approximately 1.0 cm. Style color: 145B. Ovary diameter: Approximately 2.0 mm. Ovary color: 144A.

Seed and fruit production: Neither seed nor fruit production has been observed.

Disease and pest resistance: Resistance to pathogens and pests common to *Calibrachoa* has not been observed.

What is claimed is:

1. A new and distinct cultivar of *Calibrachoa* plant named 'Balcabinsta', substantially as herein illustrated and described.
